UNITED STATES PATENT OFFICE.

JOSEPH W. NORCROSS, OF LOCKPORT, NEW YORK.

PULLEY-BLOCK.

SPECIFICATION forming part of Letters Patent No. 242,965, dated June 14, 1881.

Application filed April 25, 1881. (No model.)

To all whom it may concern:

Be it known that I, JOSEPH W. NORCROSS, a citizen of the United States, residing at Lockport, in the county of Niagara and State 5 of New York, have invented new and useful Improvements in Pulley-Blocks, of which the following is a specification.

This invention relates to improvements in pulley-blocks for use on ships and for other 10 purposes.

The invention consists in a novel construction of the frame of the pulley-block and the sheave-pulley, and the improvements will be fully hereinafter described in detail, and pointed out in the claims.

This invention is illustrated in the accompanying drawings, in which Figure 1 represents a side elevation of my pulley-block. Fig. 2 is a section in the plane $x x$, Fig. 1. Fig. 3 20 is a section in the plane $y y$, Fig. 1. Fig. 4 is a face view of the sheave.

Similar letters indicate corresponding parts.

In the drawings, the letters $A A$ designate the metallic frames, which are of skeleton form. 25 $B B$ are the cheeks, which fit into rims $a a$, formed on the metallic frames and cast solid with the same. The skeleton metallic frames are arranged upon the outside faces of the wooden cheek-pieces and the inwardly-projecting rims extend over the outer marginal edges of the cheeks and hug the same closely, so that said cheeks are prevented from splitting. In the inner faces of the cheeks are formed recesses for the reception of metallic strips C . The cheeks $B B$ and the frames $A A$ are secured together by end pieces, D , which are cast solid with pins $d d$, that project transversely through the cheeks and frames and are riveted on the outside. Instead of these pins, 40 however, rivets may be used which extend transversely through the frames and the cheeks and through holes formed for their passage in the end pieces. In the central portion of the skeleton frames and in the cheeks and the 45 straps $C C$ are formed holes, which form the bearings for the center pin, e , on which is mounted a sheave, E . The end pieces serve to support the hook F and the becket G .

The sheave E consists of a metallic rim, d' , 50 the inner periphery of which is slightly tapering outward from the middle, (see Fig. 2,) while

its outer periphery forms a groove, e , for the reception of the rope. Into the interior of the rim d' are fitted two wooden disks, ff , and on the outer surface of each of these disks is placed a metallic strap, g , which extends diametrically across, so that its ends bear against the inner periphery of the rim. Through each of these straps and through the wooden disks extends two rivets, $h h' h' h'$, which are riveted 55 on both ends, so that the straps and the disks are firmly connected to each other. From one of the straps projects a hub, i , through the wooden disks and through the other strap, and this hub is bored out to receive the center pin. 60 From the inner tapering surfaces of the rim projects a rib, j , (one or more,) which engages with a notch (one or more) in the wooden disks, so as to prevent them from turning in the metallic rim.

By these means a pulley-block is obtained which is extremely firm and durable, and which can be made at a comparatively small expense.

I do not claim, broadly, in this application for a patent the combination of metallic frames 75 with the cheeks of a pulley-block, such frames forming the subject-matter of a prior application for a patent.

What I claim as new, and desire to secure by Letters Patent, is—

1. A pulley-block embodying in its construction wooden cheek-pieces and metallic frames arranged on the outside faces of the wooden cheeks, and each constructed with inwardly-projecting rims at their outer edges, which embrace the outer margins of the wooden cheeks, said metal frames and wooden cheeks being connected together by end pieces interposed between the cheeks and transverse pins passing through the cheeks and the metal frames, 85 all substantially as described.

2. The combination of the metallic frames arranged on the outside faces of the wooden cheek-pieces, and each constructed with inwardly-projecting rims at their outer edges, 95 which embrace the outer margins of the cheeks, with end pieces interposed between the wooden cheeks, and each provided at its opposite sides with attached lateral pins projecting through the cheeks and metallic frames, and secured in 100 place substantially as described.

3. The metallic rim d' , having on its inner

periphery a transverse spur, *j*, (one or more,) in combination with two wooden disks having their peripheries transversely penetrated by the spur, said disks being connected together 5 and provided with exterior straps, forming bearings for the axial pin of the pulley-block.

4. The combination, substantially as described, of the metallic rim *d'*, the wooden disks fitting the interior of said rim, and a rib, *j*, (one or more,) projecting from the inner surface of the rim for engaging with a notch (one or more) in the disks.

5. The combination, substantially as herein-before described, of the metallic rim *d'*, the wooden disks *ff*, fitting the interior of said rim, the straps extending diametrically across the wooden disks, the rivets for securing the straps and the wooden disks together, and the hub projecting from one strap through the disks and through the 20 wooden disks and through the other strap.

6. The combination, substantially as herein-before described, of the metallic rim *d'*, the wooden disks fitting the interior of said rim, the ribs projecting from the inner surface of the rim and engaging with notches in the disks, 25 the straps extending diametrically across the wooden disks, the rivets for securing the straps and disks together, and the hub projecting from one strap through the disks and through the other strap.

In testimony whereof I have hereunto set my hand and seal in the presence of two subscribing witnesses.

JOSEPH W. NORCROSS. [L. S.]
